UNITED STATES PATENT OFFICE

OSCAR F. NELSON, OF CHICAGO, ILLINOIS

DOOR SILENCER

Application filed December 13, 1930. Serial No. 502,197.

The present invention relates to a door silencer and has for its prime object to provide an exceedingly simple device which is inexpensive to manufacture and designed for 5 the purpose of association with the door to prevent the noise incident to the slamming or closing of the door.

Another very important object of the invention resides in the provision of a device 10 of this nature which is thoroughly efficient and reliable in use and otherwise well adapted to the purpose for which it is designed.

With the above and numerous other objects 15 in view as will appear as the description proceeds, the invention resides in certain novel features of construction, and in the combination and arrangement of parts as will be hereinafter more fully described and claimed.

20 In the drawings:

Figure 1 is a perspective view showing a doorway with the devices mounted on one side thereof adjacent the hinges of the door.

25 Figure 2 is a view showing the hinged edge of a door with the devices mounted thereon.

Figure 3 shows one of the three corners of a door with a device mounted thereon.

Figure 4 is a view showing the devices on a hinge, and

30 Figure 5 is a longitudinal section through one of the devices.

I will first describe one of the devices in detail and particular attention is directed to Figure 5. Numeral 5 denotes an oblong 35 plate with ends 6 bent thereover to form pockets for receiving the ends of a strip of rubber or similar material denoted by the numeral 7 and the intermediate portion of this strip is bowed outwardly from the plate. The ends of the strip are anchored in the pockets by screws 8 which are also utilized to anchor the device.

40 The devices may be mounted on the side 45 of the doorway adjacent the hinges as indicated in Figure 1, or the devices may be mounted on the hinged edge of the door as is indicated in Figure 2 or the device may be mounted on the free end of the door as 50 is indicated in Figure 3 or the device may

be mounted on the leaves of the hinges as indicated in Figure 4.

Of course the device may be used in other ways but it is thought that the examples given are sufficient to appreciate the utility and 55 advantages of the invention.

It is apparent that changes in the details of construction, in the dimensions, and in the materials of the device may be resorted to without departing from the spirit or scope 60 of the invention as hereinafter claimed or sacrificing any of its advantages.

Having thus described my invention, what I claim as new is:

Means for silencing the closing action of 65 a door comprising a flat plate of elongated form having its ends bent to provide loops to form pockets at the ends of the plate, a rubber strip of greater length than the plate and having its ends placed in the pocket 70 whereby the intermediate portion of the strip is pulled outwardly from the plate, and fastening elements passing through the looped ends of the plate and through the ends of the strip into a part of the door to hold the 75 device on the door and to hold the ends of the strip in the pocket.

In testimony whereof I affix my signature.

OSCAR F. NELSON.
